UNITED STATES PATENT OFFICE.

MYRON F. HILL, OF NEW YORK, N. Y.

SHIP.

Application filed March 27, 1919, Serial No. 285,506. Renewed May 9, 1923.

To all whom it may concern:

Be it known that I, MYRON F. HILL, citizen of the United States, resident of the county, city, and State of New York, have invented an Improvement in Ships, of which the following is a specification.

This invention relates to ships and particularly such as set forth in my co-pending application Serial No. 267,480 $\frac{1}{2}$, filed December 19, 1918, Ships.

The principal object of the present invention is a ship built of sections, preferably of cast steel, with longitudinal stiffeners and transverse frames and adapted to be joined into a hull to withstand various stresses and strains to which a structure of this character may be subjected.

A further object is to build a ship at less cost, in less time, of greater carrying capacity, lighter weight, and of greater strength than an ordinary ship.

My invention relates to further features and details of construction which will appear in the further description.

In the drawings:

Fig. 1 shows the general lines of the ship.

Figs. 2 and 3 show the shell expansion.

Figs. 4 and 5 show the typical deck construction.

Fig. 6 shows a midship section.

Fig. 7 shows the keel and the method of assembling its sections.

Fig. 8 shows the arrangement of floors and their relation to the tank top and outer bottom.

Figs. 9 and 10 show a method of attaching stanchions to the deck beams and fore and aft girders.

Figs. 11 and 12 illustrate sections through hatchways.

Fig. 13 shows the method of attaching the transverse frames to the tank top.

Fig. 14 shows a longitudinal section through the shell on line A—A, and the form of butt joints.

Fig. 15 shows a method of joining frames of adjacent shell sections where the registry is not exact.

Fig. 16 shows a midship section in the boiler space.

Fig. 17 illustrates an alternative method of joining the shell, and tank top sections when the stakes are arranged on the "in and out" plan instead of being joggled.

Fig. 18 shows a typical casting section for joggled plating.

Fig. 19 shows a typical casting section for "in and out" plating.

Fig. 20 shows a cross section through a casting section.

In the drawings numbers 1 to 38 inclusive show transverse sections of the ship from stem to stern divided into 37 equal divisions between numbers 1 and 38, with an extra division and a fraction between number 1 and the forward perpendicular and a fraction between number 38 and the after perpendicular, which is represented at AP. It is apparent from this drawing that a straight edge resting against the hull in a vertical position will make contact from the top of the hull down to the bilge, except in way of the knuckles where two planes intersect. These lines may not in final construction be perfectly straight since they are affected by the torsional warping of the sections when drawn into position, but so far as the casting system is concerned they are straight and may remain straight until assembly. The curves of the forward and after castings in horizontal planes may be effected in the annealing oven or by any other suitable means. The bilge represented by the curved portion of the lines 1 to 37 may for the most part have a single curvature throughout. It is of course apparent that the right hand side of Fig. 1 shows the forward body and the left hand side of Fig. 1 shows the after body. The curvature at the bilge of lines 1 to 24 is preferably uniform. The curvature of lines 25 to 36 may be of larger radii if desired. It is of course apparent that the curvature of lines 1 to 24 may also have increased radii. This curvature may match the curvature of lines 25 to 36, if desired, thereby somewhat standardizing castings for these portions of the ship. It will be noted that lines 1 to 11 are straight from the bilge to the top of the hull. This is of course true also of the lines 11 to 24 of the middle body. The lines of the after body are modified by the two knuckles 39 and 40, the knuckle 39 being for the most part below the water level and the knuckle 40 representing the line of the shelter deck. The broken line 41 shows the location of the upper deck in the after body; the line 42 shows the location of the upper deck in the forward body. Line 43 shows the location of the shelter deck in the forward body. Line 44 shows the forecastle deck and line 45 shows the poop deck. It will

be noted that these decks have a sheer, which is most desirable for ship construction but which is difficult if not impossible to obtain under the ordinary fabricating systems without losing the fabricating principle.

While Fig. 1 shows the theoretical lines of the ship, the lines 46 in Figures 2, 3, 6, 16, and 17 indicate the location of the frames of the ship. The frames are preferably normal to the shell throughout the length of the ship in order to maintain uniformity in the castings. The side frames of the ship register with the floors in the inner bottom of the ship and with the deck beams of the various decks. There is a floor at every frame. In certain places additional floors may be provided for further local stiffening of the ship if desired.

20 Hatchways 47, shown in Figs. 4 and 5, 11 and 12, may be provided in the decks, and derrick foundations of the usual type can be mounted between the hatchways. The usual superstructures may be erected in any 25 suitable way. Suitable stanchions 48, shown in Fig. 6, may be provided wherever desired. Water-tight flats 49 and 50 shown in Figs. 2 and 3 may be employed wherever desired for the purpose of forming boundaries to trimming or ballast tanks of the usual type.

In Figs. 2 and 3 are shown the method of assembling of the shell sections. The lines 46 illustrate the transverse frames and 35 lines 51 the side stringers for the ship as built upon the transverse system of framing. In these figures the full lines represent the sight edges of the casting sections. The number of short diagonal lines intersecting the full lines indicate whether a seam or butt joint is to be single, double, treble or quadruple riveted. For example; two 40 lines represent double riveting, three lines treble riveting, and four lines quadruple riveting.

45 In Figs. 4 and 5 is shown the typical deck construction for the upper deck with the hatchways 47. The deck beams 52 are shown in broken lines and the longitudinal 50 seams and transverse butt joints are shown by full lines. As in the case of the shell, the number of short diagonal lines intersecting the full lines indicate whether a seam or butt joint is to be single, double, treble or quadruple riveted. The arrangement of 55 bulkheads 53 is also shown. The bulkheads in the forward and after bodies follow as far as possible the direction of the deck beams and at the bottom as far as possible 60 the direction of the floors so that the bulkheads register with the deck beams and floors. It will be noted that the deck beams 52 in the forward body are normal to the shell thereby registering with the side 65 frames. The construction for all decks

is similar to the upper deck described above, as is also the tank top construction.

In Fig. 6 is shown the midship section. Keel castings composed of H girder sections 54 may be formed as shown in Fig. 70 7. The different sections of the H girders may be dovetailed together as represented at 55, and the dovetailing edges where they lap are united together by riveting. The top and bottom flanges of the H girders as well 75 as the web have the ends which lap on to the adjacent casting, joggled so that the keel sections will be in alignment. The forward end of the keel may be riveted to the stem casting and the after end of the keel 80 to the stern frame making a solid and rigid backbone for the ship.

In Fig. 6 is indicated the method of assembling the sections in erecting the ship as follows. A bottom shell casting; for 85 example 56, consisting of a portion of a floor 57 and a portion of a side girder 58 extends from the keel 54 to line 59. A similar tank top casting 60 extends from the keel 54 to line 61 which consists of a 90 portion of a number of floors 62 and a portion of a side girder 63. The shell casting and tank top casting are riveted together at 64 and 65 by double riveted lap joints, and also to the keel at 66, 67, and 68, by 95 double riveted joints. Similar sections extend from line 59 to line 69. The bilge shell section extends from line 69 to line 70 and side shell sections from line 70 to line 71, line 71 to line 72, line 72 to line 100 73, and from line 73 to the top of the sheer strake at 74. Lightening holes 75 are provided in the floors as are also drainage and vent holes 76. All the sections may be cast in one length, except at the ends of the ship, 105 and joints in the shell being staggered to provide a satisfactory shift of butts. A portion of a margin plate 77, side stringer 78 and deck stringer 79 may be cast integral with the corresponding side section, in addition to a portion of a number of frames 110 46. The transverse frames may be riveted to the tank top at 80 by a lap which is cast on the lower edge. The deck sections 81, 82, and 83 may be cast similar to the outer bottom, tank top, and side sections, and when assembled may be held partly in place 115 by the stanchions 48. Deck sections 81 are riveted to the deck stringers at 84, and deck sections 83 have a flange cast on and are 120 riveted to the shell at 85. The stanchions 48 are secured to the decks by separate castings 86 and 87, shown in Figs. 9 and 10, respectively, which are riveted to both the 125 deck beams 88, and 89, and the fore and aft girders 90. At the bottom of the stanchions separate castings 91 may be riveted to the tank top or deck and to the hollow stanchions 48. Beam knees 92 may be cast as 130 part of deck beams 88 and 89 and riveted

to the frames. The bulwarks 93 may be formed of rolled plate riveted to the sheer strake and to the cast supports 94, which are in turn riveted to the deck sections.

Fig. 8 shows a longitudinal section through the inner bottom with the upper and lower portion of floors riveted together at 64. The bulbs 95 are provided simply for casting purposes and are not necessary to the structural strength of the ship.

Figs. 11 and 12 show, respectively, sections through the upper deck and shelter deck hatches with the method of attachment of the hatch coaming to the deck beams and deck, to which they are riveted. It will be noted that the hatchways in any deck may be uniform throughout the ship if desired, so that a single casting for the shelter deck hatchways may be utilized, and for the upper deck hatchways another casting may be utilized which may be standard for the upper deck.

Fig. 15 illustrates the method of joining adjacent shell sections where the registry is not exact. A liner of required thickness may be inserted between the webs of frames of adjacent sections and riveted to both webs.

In Fig. 16 is shown a modification of the midship section for the boiler and engine space. The upper deck section 81^a is inclined (the deck beam being bent up to the right of line 96). Supporting stiffeners 97 and brackets 98 may be riveted to the deck beam 89 above and to the upper deck sections 81 and 81^a by means of flanges 99 cast integral with them. An additional stiffener 100 may be utilized to stiffen the coaming being riveted to the deck beam 101 of the bridge deck. Deck sections 83 and 102 are flanged for riveting to the hatch coaming. Any suitable superstructure metal 103 may be added as indicated, being riveted to the deck 102.

Fig. 17 illustrates an alternative method of forming the shell sections. The strakes are "in and out" instead of the plates being joggled. This involves practically the same details of construction as the first method outlined.

The bulkhead construction may be similar to that described in my application for patent, Serial No. 267,480¹, filed December 19, 1918, except the sections which may be of uniform width are joined together by riveting instead of welding. Joggled laps may be cast upon the sections or the sections may lap to form "in and out" strakes. As there are no deck longitudinals the stiffeners are bracketed securely to the deck plating.

If preferred, vertical stiffeners may be used in place of the horizontal stiffeners shown. Rolled plate may be used if desired

where the plating is too thin for economical casting.

The frame construction in the extreme forward and after sections is similar to that indicated in Figs. 6 and 17 for the midship section, the frames being lengthened or shortened where necessary to suit local requirements.

The shaft tunnel construction may be similar to that described in my application for patent, Serial No. 267,480¹, filed December 19, 1918, or modified as desired.

The floor construction is as shown in Figs. 6 and 17. Where watertightness or oiltightness is required the lightening holes 75 and the drain and air holes 76 are omitted and the riveting between the upper and lower portions of the floors and to the keel is made water tight or oil tight as the case may be.

The side girders may have lightening holes similar to those shown for the floors in Figs. 6 and 17, except in way of ballast or other tanks. Two side girders are provided on each side of the ship running throughout the major portion of the length of the ship, and a third is added for a short distance in the extreme after portion of the ship. These side girders are ordinarily cast with the outer bottom or tank top sections, being lapped and riveted together, but side girders of rolled plate may be used at the ends of the ship if desired.

The details of the stem and stern post may be as described in my application for patent, Serial No. 267,480¹, filed December 19, 1918, with a few modifications to adapt them to a riveted ship. A recess is preferable in the stem and stern post castings which will allow the shell sections to lap on to them forming a flush surface on the outside. The shell sections are lap riveted to the stern and stem post castings through this lap. The keel is riveted to the stem at the forward end and to the stern post at the after end.

Figs. 18 and 19 show the typical casting sections which are used in assembling the shell, tank top and decks. These sections are riveted together to form the ship. Fig. 18 shows a casting section with two edges joggled, which may be assembled as indicated in Fig. 6, and Fig. 19 shows a casting section without joggling which may be assembled as indicated in Fig. 17. In the figures the transverse frames 104 and stringer 105 are cast integral with the plating 106, the plating being oblong as shown. The stringers 105 project beyond the edge of the plate at 107 where a joggle is cast which will allow the opposite end of the stringer 125 on the adjacent casting to rest upon it and be riveted thereto. Stringers 105 have bulbs cast on their lower edges. Lugs

108 and 109 are also cast as wings to the ends of these stringer bulbs as shown in Fig. 20, to enable the bulbs to be spliced to their full or partial strength. The castings are 5 poured by means of gates, through bulbs 111 on the lower edge of the frames, which leave the forms indicated at 110. The cross section of the latter bulbs is preferably circular. Lugs 112 and 113 are also cast to the frames to allow for the splicing of the bulbs of the frames. The webs of the frames are lapped and riveted at 114.

In Fig. 18 the plating is joggled on two edges at 115 and 116. This allows the edges of the adjacent castings to rest upon these laps, thus forming a flush surface on one side of the plating. The joints are formed by riveting the two adjacent sections together in the customary manner. Joints may be single, double, treble or quadruple riveted according to the requirements. In Fig. 19 no joggling is shown on edges at 117 and 118. With this form of casting the plating laps on the adjacent casting forming "in and out" strakes on the side of the ship. The stringer webs and frame webs are however joggled to provide simplification in the connection of frames and stringers. The laps are cut off at 119 in all cases to avoid three thicknesses overlapping where the corners of three castings join. To make these corners water-tight special caulkings is required. On any one casting section the diagonally opposite corners are the ones so cut. Lugs 120 are formed in the vents in the mould and are cut off during trimming as are also the forms 110 at 121.

The method of molding is similar to that described in my application for patent, Serial No. 267,480¹, filed December 19, 1918.

All the sections are so designed as to be standardized. There may be several different standard sections such as for outside plating, tank top plating, deck plating and bulkheads. Portions of sections may be formed where required either by coring in the moulds or trimming after the castings are made.

The ship is built by assembling the sections with the plates 106 (see Figs. 18 and 19) arranged in horizontal strakes, each section having its greatest dimensions lengthwise of the hull as shown in Figs. 2 and 3. The joints between the strakes are reinforced by the longitudinal stiffeners which are also joined. The sections are also joined transversely, the joints being reinforced by the transverse frames, floors and deck girders, which join the longitudinal stiffeners. The frames, floors and deck girders are also joined.

The method of construction shown eliminates a considerable amount of the riveting found in an ordinary rolled plate ship, by doing away with boundary and connection

angles, and by substituting cast sections for those built up of rolled shapes riveted together.

A steel ship having a dead weight carrying capacity of 9600 tons built of rolled plate and shapes, would have this carrying capacity increased to about 9800 tons if built of cast sections thus increasing the efficiency of the ship.

The seams and butts of this ship may be 75 caulked in the usual manner.

I have designed the ship with particular relation to casting, but it is possible to build it up partly of rolled metal.

While I have described my invention in 80 the form in which it seems preferable to construct it, I do not limit myself to the particular details shown for they may be varied without departing from the fundamental idea of the ship.

What I claim is—

1. In a ship, horizontally disposed strakes of plates, each composed of separately formed integral units each having its greatest dimension lying lengthwise of the hull, 90 and including a plurality of stiffeners, such as frames or floors, disposed across the said greatest dimension.

2. The combination claimed in claim 1, 95 each unit including also an integral longitudinal strength frame stiffener, stringer or girder.

3. The combination claimed in claim 2 having said longitudinal member lying 100 along one edge of said unit.

4. In a ship's hull horizontally disposed strakes of plating composed of duplicate sections, each section having vertically disposed portions of stiffeners of shallow depth integrally formed with the plating of said 105 sections.

5. The combination claimed in claim 4 having deeper girder portions at right angles to said shallow stiffener portions integrally formed with said plating.

6. The combination claimed in claim 4 having said sections cast with offset edges adapted to overlap each other for joining purposes.

7. The combination claimed in claim 5, 115 having said sections cast with offset edges adapted to overlap each other for joining purposes.

8. A ship's hull comprising strakes of even width in its curved and flared ends, 120 said strakes comprising sections having transverse stiffener portions disposed thereon at equal angles.

9. The combination claimed in claim 8, 125 having overlapping offset edges cast integrally with said sections for joining purposes.

In testimony whereof, I have affixed my signature to this specification.

MYRON F. HILL.
